CLAIM

The ornamental design for a cosmetic spatula, as shown and described.

DESCRIPTION

FIG. 1 is a perspective view of the cosmetic spatula, showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depicting portions of the cosmetic spatula are for illustrative purposes only and form no part of the claimed design.
